INVENTOR

J. J. BRAZNELL

BY *E. C. Kugman*
ATTORNEY

UNITED STATES PATENT OFFICE.

JOHN J. BRAZNELL, OF ST. LOUIS, MISSOURI, ASSIGNOR TO AMERICAN BED COMPANY, OF ST. LOUIS, MISSOURI, A CORPORATION OF MISSOURI.

FOLDING BED.

Application filed August 9, 1924. Serial No. 731,174.

To all whom it may concern:

Be it known that I, JOHN J. BRAZNELL, a citizen of the United States of America, residing at the city of St. Louis, State of 5 Missouri, United States of America, have invented a certain new and useful Folding Bed, of which the following is such a full, clear, and exact description as will enable anyone skilled in the art to which it appertains to make and use the same, reference being had to the accompanying drawings forming part of this specification.

My invention relates to a folding bed and particularly to that type of folding bed 15 known as sofa beds or day beds.

The object of my invention is to produce a simple, rigid and strong folding bed of the type named, to secure ease of manipulation and to provide ample storage space for the 20 bedding when the device is in its folded position.

In the accompanying drawings, which illustrate so much of one form of folding bed as is necessary to illustrate my invention, 25 Figure 1 is an end elevation; Figure 2 is a top plan view of one end; and Figure 3 is an enlarged cross section showing the device in folded position.

In order to simplify the drawings I have 30 omitted the ornamental end pieces usually applied to beds of this type as well as the permanent textile covering for the spring fabric, necessary to enable the device to function as a sofa or couch, and also several braces which are not essential to the 35 operation of the device.

Each of the end frames comprise a pair 40 of uprights 5, preferably of angle iron, and upper and lower cross bars 6 and 7 respectively. The two end frames are connected by an angle bar 8 extending between the upper ends of one pair of uprights, and angle bar 9 extending between the lower ends of the other pair, and by a flat bar 45 10 secured to the lower cross bar 7 at points intermediate their ends. Extending between the bars 8 and 10 are a number of metal straps 11, preferably curved at one end, as shown, and forming one part of 50 the bottom of the receptacle for the bedding, the other part being formed, when the device is in folded position, by a section of the spring frame as will be hereinafter more fully set forth.

55 Figures 1 and 2, preferably provided with

casters 13, support one edge of the spring frame which comprises three sections 14, 15 and 16 carrying the spring fabric 17 which may be of any suitable type. The section 14 is pivoted to the section 15 at the point 60 18, and the section 15 to the section 16 at the point 19. Connecting the central section 15 to the end frames are a pair of links 20 and 21 situated at each end of the bed, the links 20 being pivoted to the cross bar 7 and 65 the links 21 to the cross bar 6. Section 16 is also connected to the end frames by links 22 pivoted to the cross bar 6 adjacent to the links 21. The angle irons composing the section 14 are connected by a strut prefer- 70 ably formed of tubing and bowed to prevent contact with the fabric 17. A similar strut 24 connects the angle iron of the section 15 while those of the section 16 may be connected by an angular strut 25 ar- 75 ranged at the ends. Each of the links 21 is provided with an extension to which is attached one end of a helical spring 26, the other end of which is attached to the angle bar 8.

When the device is to be used as a bed the spring frame is extended as shown in Figures 1 and 2, the double link connection to the central section, together with the end link 22 and the rigid legs 12 forming a firm 80 support. To fold the device into couch or sofa form the section 14 and legs 12 are forced toward the end frames until the parts assume the position shown in Figure 3, the center section forming the front of the 85 couch and the section 16 being reversed and brought into alignment with the straps 11 to cooperate with said straps in forming the bottom of the receptacle for the bedding. The closing movement is assisted by 90 the spring 26 which thus overcomes the difficulty which would otherwise be experienced in moving the parts into closed position. Ample space for the bedding is secured be- 95 tween the bottom, formed of the straps 11 and the section 16, and the top formed of the section 14 and access to this space is readily obtained by raising the section 14, 100 on the hinges 18.

Having fully described my invention, 105 what I claim as new and desire to secure by Letters Patent of the United States is:

1. In a device of the class described, the combination with a pair of end frames, of a spring frame comprising three sections, the 110

outer section being provided at its outer side with supporting legs and pivoted at its inner side to the intermediate section, the inner section being pivotally connected 5 to the end frame and to the intermediate section, whereby it is reversed when in folded position, and a pair of links at each end connecting the intermediate section to the end frame, said links being so proportioned and positioned as to hold the intermediate section in horizontal position when 10 extended and approximately vertical position when folded.

2. In a device of the class described, the 15 combination with a pair of end frames, of a spring frame comprising three sections, the outer section being provided at its outer side with supporting legs and pivoted at its inner side to the intermediate section, 20 the inner section being pivoted to the intermediate section and connected by a link to the end frame, a link connecting the inner side of the intermediate section to the end frame, said link being longer than the first 25 named link, and a third link connecting the outer side of the intermediate section to the end frame, said third link being longer than said second named link.

3. In a device of the class described, the

combination with a pair of end frames, 30 of a spring frame comprising three sections, the outer section being provided at its outer side with supporting legs and pivoted at its inner side to the intermediate section, the inner section being pivoted to the intermediate section and connected by a link to the end frame, a link connecting the inner side of the intermediate section to the end frame, 35 said link being longer than the first named link, said second named link being provided with an extension to which is attached a spring to assist in folding the bed, and a third link connecting the outer side of the intermediate section to the end frame, said third link being longer than said second named link.

4. In a device of the class described, the combination with a pair of end frames, of a partial receptacle bottom carried between 40 said frames, and a sectional spring frame having link connection to said end frames, one section of said spring frame when in folded position aligning with said partial receptacle bottom to complete the same.

In testimony whereof, I have hereunto 45 set my hand this the 7th day of August, 1924.

JOHN J. BRAZNELL.
